UNITED STATES PATENT OFFICE.

JOSEPH SCHECHTER, OF BROOKLYN, NEW YORK.

LOCK MECHANISM.

Application filed January 10, 1922. Serial No. 528,180.

To all whom it may concern:

Be it known that I, JOSEPH SCHECHTER, a citizen of Poland, residing at Brooklyn, in the county of Kings and State of New York, have invented certain new and useful Improvements in Lock Mechanism; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to improvements in lock-mechanisms; and the invention has reference, more particularly, to improvements in the construction and actuating means of locks of the rotary dead bolt type such as is shown and described in the prior Letters Patent of the United States heretofore granted to me, dated October 18th, 1921, and numbered 1,393,835.

25 The present invention has for its principal object to provide, in combination with a rotary dead bolt mechanism, a novel actuating means having combined therewith a hand manipulatable knob and a key operated means, said actuating means having a novel coupling mechanism for connecting said key operated means with said actuating means in normal operative relation thereto, and said knob having means for automatically disconnecting said coupling mechanism from said key operated means when said knob is employed to operate said actuating means, so that the key operated means is not disturbed but remains inactive and 40 uncoupled from the actuating means when the latter is operated by the knob.

Other objects of the present invention, not at this time more particularly enumerated, will be clearly understood from the following detailed description of the same.

45 With the various objects of the invention in view, the same consists, primarily, in the improved lock mechanism hereinafter set forth; and, the invention consists, furthermore, in the novel arrangements and combinations of the several devices and parts, as well as in the details of the construction of the same, all of which will be more fully described in the following specification, and

then finally embodied in the claims appended thereto.

The invention is clearly illustrated in the accompanying drawings, in which:

Figure 1 is a top edge elevation and part section of the novel lock mechanism as applied to a door and door frame; Figure 2 is a longitudinal section taken on line 2—2 in said Figure 1, and showing the lock mechanism in locked position; Figure 3 is a view similar to that shown in Figure 2, but showing the lock-mechanism in an initial stage of its releasing movement as controlled by the knob device thereof, and further showing the actuating means uncoupled from the key operated means; Figure 4 is a transverse longitudinal section, taken on line 4—4 in said Figure 2; Figure 5 is a fragmentary section similar to that shown in Figure 4, but illustrating the manner in which the knob device operates to disconnect the coupling means from operative relation to the key operated means; Figure 6 is a fragmentary or detail horizontal section, taken on line 6—6 in said Figure 4, and drawn on an enlarged scale; Figure 7 is a similar fragmentary or detail horizontal section, taken on line 7—7 in said Figure 5, also drawn on an enlarged scale; and Figure 8 is a side elevation of the novel knob device detached from the lock mechanism.

Similar characters of reference are employed in all of the hereinabove described views, to indicate corresponding parts.

Referring now to said drawings, the reference character 1 indicates a casing for enclosing the lock-mechanism, the same having in one end wall suitably disposed openings 2 and 3 to permit the passage of the dead bolt when the latter is operated. The reference character 4 indicates a rotary dead bolt of substantially semi-circular shape, and provided adjacent to one end with an inwardly projecting radial arm 5, the free inner end of which is pivotally mounted on a fulcrum stud 6 fixed within the casing 1 intermediate the openings 2 and 3.

The reference character 7 indicates a tail-piece, the forward end of which is pivotally connected with a coupling stud 8 provided on said radial arm 5 of said rotary bolt. Said tail-piece 7 is provided adjacent to its rearward end with a substantially circular opening 9, the inner surface or walls of

which cooperate with the means provided for actuating said tail-piece to in turn operate the rotary bolt 4. Extending forwardly and longitudinally in said tail-piece 5 from said opening 9, and in communication with said opening, is a guide-slot 10. Fixed within said casing so as to extend transversely therethrough in a location spaced rearwardly from and alined with the 10 fulcrum point of said rotary bolt 4 is a guide-post 11 which projects through said guide-slot 10 of said tail-piece so as to control and guide the operative movements of said tail-piece when the latter is actuated. 15 In order to support said tail-piece, when actuated, against lateral displacement relative to the other members of the lock mechanism, the rear extremity of said tail-piece is provided with a laterally projecting supporting stud or leg 12, the end of which rides on the inner surface of the front wall of said casing 1.

The outer wall of said casing is provided with a suitably disposed opening 13 which 20 provides a bearing in which is journaled the hub 14 of an actuating cam member 15. Said actuating cam member 15 is preferably of elliptical outline, whereby its extremities 16, which are alined with its longitudinal 25 axis, provide depressing cams for purposes subsequently to be described. Projecting inwardly or laterally from one extremity 16 of said actuating cam member 15 is an actuator-lug 17, which is arranged so that its 30 free end cooperates with the walls or margins of said opening 9 of said tail-piece 7. Said actuating cam member 15 is so disposed relative to the normal position of said opening 9 of said tail-piece 7 as to be rearwardly eccentrically off-set therefrom, so 35 that rotation of said actuator-lug 17 by turning the actuating cam-member will cause the same to operatively engage and travel against the wall or margin of said opening 9, to thereby impart to said tail-piece the 40 movements necessary to effect the desired operation of said rotary bolt. Said actuating cam-member 15 is provided with an axial central opening 18 having longitudinally and oppositely disposed wing openings 19 connected therewith. One means for 45 rotating said actuating cam-member 15 comprises a hand-knob 20, the shank 21 of which is journaled in the opening 18 of said actuating cam-member. Integrally connected with the inner end of said shank 21 are oppositely and outwardly projecting lever lugs 22. The body of said actuating cam-member 15 is provided at its inner side with a rectangular longitudinally disposed chamber or guideway 23. In order to assemble 50 the knob operatively with the actuating cam-member, the same is turned so that said lever lugs 22 are horizontally disposed, in which position the shank 21 of the knob may be

passed inwardly through the axial central opening 18 of the cam-member, the lever lugs 22 passing through the wing openings 19 into the chamber or guideway 23. After said lever lugs 22 are entered in the chamber 55 or guideway 23, the knob 20 is given a quarter turn, whereby the lever lugs 22 are turned across the inner end of the opening 18, so as to be disposed in vertical normal position within the chamber or guideway 60 23, and at the same time engaging the bottom of the chamber or guideway intermediate the wing openings 19, thus holding the knob and its shank secure against withdrawal from assembled relation to said actuating cam-member. Arranged within said chamber or guideway 23, respectively on the opposite sides of said vertically disposed lever lugs 22, are slide-blocks 24 which normally position themselves against the sides 65 of said lever lugs 22, being yieldably held in such position by spring devices 25 interposed between said slide-blocks 24 and the ends of said chamber or guideway 23 (see Figures 4 and 6 of the drawings). One of 70 said slide-blocks 24 is provided with an outwardly projecting key-block or connector-lug 26 which projects beyond the exterior surface of the actuating cam-member 15. A cover-plate 27 is provided to extend over and close said chamber or guideway 23, the same being secured to the face of said actuating cam-member by screws 28 or other suitable fastening means; said cover plate is also provided with a slot or way 29 75 through which said key-block or connector-lug 26 projects and through which it moves when actuated.

In order to permit operation of the tail-piece and rotary bolt from the outer side of the door by means of a key controlled mechanism, the inner wall of said casing 1 is provided with a suitably disposed opening 30 which provides a bearing for a rotary sleeve or hub 31. Said sleeve or hub 31 is provided with a central slot 32 adapted to receive the end of a coupling tongue 33 of a suitable key actuated mechanism 34 connected with the outer side of the door with which said lock-mechanism is arranged. Formed in the outer side of said sleeve or hub 31, at its inner extremity, is a socket or receiving groove or seat 35 in which said key-block or connector-lug 26 normally engages itself to operatively connect, through said sleeve or hub 31, the actuating cam member 15 with the key actuated mechanism 34. In order to enable the lock-smith, when assembling the lock mechanism, to assure himself that the sleeve or hub 31 is properly positioned to be engaged both by the coupling tongue 33 and the key-block or connector-lug 26, the said sleeve or hub 31 is provided adjacent to its base with a radial tongue 36, which when visible through an 80 85 90 95 100 105 110 115 120 125 130

opening or perforation 37 provided in the inner wall of said casing, denotes that the sleeve or hub 31 is in proper normal initial position.

5 Pivottally mounted upon a suitably disposed fulcrum post 38 fixed within the casing 1 is a detent-tumbler 39, having at its free end a transverse detent-lug 40. Said rotary bolt 4 is provided, adjacent to each 10 end, with a detent notch 41. The free end of said detent-tumbler with its detent-lug 40 is normally swung toward said rotary bolt 4, and toward the actuating cam member 15, by means of a compression spring 15 42, interposed between the same and the adjacent side wall of said casing 1. The detent-lug 40 engages in either one or the other of said detent notches 41 of the rotary bolt, to retain the same against operative movement at all times, until the detent-tumbler is first actuated to withdraw 20 said detent-lug 40 from such holding engagement.

In mounting the lock-mechanism on a door, the same is secured by screws 43 to the inner side of the door 44. Connected with the door frame 45 is a bolt receiving socket or keeper plate 46, secured in place by screws 47 which pass through the flange 30 48 of said plate 46. Additional fastening of the plate 46 may be provided by inserting screws 49 through the inner wall 46' of said plate 46, the outer wall 46'' having enlarged openings 50 alined with said fastening screw positions so that a screw 35 driver may be inserted therethrough to drive said screws home. It will be noticed that when the rotary bolt 4 is turned into the socket or keeper plate 46, the same is interposed between the openings 50 and the screws 49 so that the same cannot be tampered with when the door is locked. The socket or keeper plate 46 is provided with a transverse post 51 around which the bolt 4 passes, when turned into said socket 40 or keeper plate.

The operation of the lock-mechanism when actuated from without the door by the key actuated mechanism 34 to retract 50 said rotary bolt to move the same to its released or unlocked position is as follows:

The proper key being inserted in the key actuated mechanism 34, and turned, will 55 rotate the key-barrel and coupling tongue 33 to thereby turn the sleeve or hub 31, which being normally engaged by the key-block or connector lug 26 will cause a rotation of the actuating cam member 15. As 60 the cam member 15 turns, one of its extremities 16 moves into depressing engagement with the detent-tumbler 39, swinging downwardly the same to thereby withdraw its detent-lug 40 from the engaged detent 65 notch 41 of the rotary bolt 4, and conse-

quently releasing the latter for operative turning movement. By the time the rotary bolt is thus released for movement, the rotation of the actuating cam-member 15 has carried its actuator lug 17 rearwardly into 70

operative engagement with the wall or margin of the opening 9 of said tail-piece 7, thereby imparting to the latter a rearward movement or pull. The rearward movement or pull on said tail-piece 7 is 75 transmitted to the radial arm 5 of the bolt 4 causing an inward swinging movement of the same which imparts a rotary movement to the bolt 4, whereby the free end of the latter is withdrawn outwardly through the 80 opening 2 in the casing end. Continued rotation of said cam-member 15 carries the actuator-lug 17 past the center of its swing and starts the same around in a forward direction toward the starting point. This 85 movement tends to pull the tail-piece 7 up to the limit of its rearward movement, and thereupon swings the same laterally upon the guide-post 11 as a fulcrum, so that the radial arm 5 is swung past the 90 center of its rearwardly turning movement, whereupon the actuator-lug in swinging forward tends to push forwardly the tail-piece 7 consequently continuing the rotary movement of the bolt 4. As the actuator-lug 17 approaches the completion of its rotation it pushes the tail-piece 7 forwardly until the radial arm 5 is swung to stopped 95 position against the end of the casing 1, the attainment of which position completes 100 the rotary movement of the bolt 4, so that its free end is withdrawn into the casing 1 flush with the opening 3. The actuator-lug 17 upon completion of its rotation is stopped against the side of said slot 10 105 adjacent the junction of the latter with the opening 9. It will be understood, that the completion of the operative rotation of the cam-member 15 operates to position the same, so that said detent-tumbler 39 110 is free to swing back to normal position with the detent-lug 40 operatively engaged with a detent notch 41 of the rotary bolt. The above operations withdraw or rotate 115 the bolt 4 from or out of the socket or keeper-plate 46, so that the door is released for opening movement.

The operation of the lock-mechanism when actuated from within the door by the hand knob to retract said rotary bolt to move the 120 same to its released or unlocked position is as follows:

The hand knob 20 is turned, thereby rotating the lever lugs 22 before any movement is imparted to the actuating cam member 15. This initial rotation of said lever lugs 22 carries one lever lug against one slide block 24 and the other lever lug against the opposite slide-block 24, thereby pressing the 125 same outwardly in the chamber or guideway 130

23 against the tension of the springs 25, and until the slide blocks are stopped against the ends of said chamber or guideway. Since the key-block or connector-lug 26 is mounted 5 upon or carried by one of said slide-blocks 24, it follows that the outward movement of the slide-block effected by the initial turning movement of the knob 20, moves the said key-block or connector lug 26 out of the seat 10 35 of the sleeve or hub 31, thus disconnecting said sleeve or hub 31, and consequently the key actuated-mechanism 34, from operative relation to the actuating cam member 15, preliminary to the imparting to the latter 15 of operative rotary movement, as illustrated more particularly in Figure 5 of the drawings. Upon the abutment of said slide-blocks 24 against the ends of the chamber or guideway 23 the independent preliminary 20 rotary movement of said knob 20 ceases and thereafter continued turning of the knob 20 operatively rotates said cam-member 15, while at the same time holding said key-block or connector-lug 26 in disengaged position, as shown in Figure 3 of the drawings. Rotation of said cam-member 15 operates upon the tail-piece 7 to actuate the rotary bolt 4 in the same manner as is already above described. 25 30 While it is preferable to employ two slide blocks 24 in the manner above described and as shown in the drawings whereby a balanced pressure on the knob 20 is assured, it is really only essential that the slide-block 35 on which the key-block or connector-lug 26 is carried be used, so that if desired the opposite slide-block could be omitted.

It will be understood, that by reason of the novel means comprised in the arrangement of knob 20, lever lugs 22 and slide-block 24 carrying the key-block or connector-lug 26, the knob may be employed to turn the actuating cam member 15 without disturbing or moving the key actuated mechanism from a normal position, and that consequently no disarrangement of the key actuated mechanism will occur, all of which is highly desirable.

It will also be understood, that the rotary bolt 4 may be projected to locked position by reversing the rotation of the actuating cam member, through either the medium of the knob 20 or key actuated mechanism 34, in which case the movements of the tail-piece 7, as above described, will be reversed.

I am aware that some changes may be made in the several arrangements and combination of the various devices and parts as well as in the details of the construction of the same, without departing from the scope of the present invention as above described, and as defined in the appended claims. Hence, I do not limit my invention to the exact arrangements and combinations of the 60 65 parts set forth in said specification, nor do I

confine myself to the exact details of the construction of said parts as illustrated in the accompanying drawings.

I claim:

1. In a lock, the combination with a bolt 70 mechanism of a rotary actuating cam therefor, a key actuated mechanism, said actuating cam having a movable connector-lug normally engaged with said key actuated mechanism to couple the same operatively with 75 said actuating cam, a hand-knob associated with said actuating cam whereby a turning movement imparted to said knob will first move said connector-lug to disengage the same from said key actuated mechanism 80 prior to imparting operative rotative movement to said actuating cam.

2. In a lock, the combination with a bolt mechanism of a rotary actuating cam therefor, a key-actuated mechanism, a rotary 85 coupling sleeve connected with said key-actuated mechanism, said sleeve having a receiving socket in its side, a spring pressed connector-lug slidably associated with said actuating cam to normally engage in said 90 receiving socket of said coupling sleeve, a hand-knob journaled in said actuating cam, said hand-knob having lever means for initially moving said connector-lug out of said receiving socket of said coupling sleeve prior 95 to imparting rotative movement to said actuating cam.

3. In a lock, a casing, a bolt device for projection from said casing, a bolt operating means, a rotary cam journaled in the front 100 wall of said casing for actuating said bolt operating means, a key actuated mechanism having a coupling tongue, a rotary sleeve journaled in the rear wall of said casing with which said coupling tongue is engaged, 105 said sleeve having in the side of its body a receiving socket, said actuating cam having a guideway in its body, a slide-block movable in said guideway, a connector-lug carried by said slide-block to normally engage 110 in said receiving socket of said sleeve, spring means for holding said slide-block in normal position, a rotatable knob projecting externally from the front wall of said casing, said knob having a shank journaled in said actuating cam, lever means on the inner end 115 of said knob for first moving said slide-block when said knob is turned to disengage said connector-lug from said receiving socket of said sleeve prior to imparting operative rotative movement to said actuating cam.

4. In a lock, a casing, a bolt device for projection from said casing, a bolt operating means, a pivoted detent means for holding said bolt against operative movement, a rotary member having peripheral cam means for releasing said detent means, said rotary member being journaled in the outer wall of said casing, said rotary member having an actuator-lug for actuating said bolt operat- 120 125 130

ing means, a rotary sleeve journaled in the inner wall of said casing, said sleeve having a receiving socket in its body, a key actuated means having a coupling tongue engaged with said sleeve, said rotary member having a movable means provided with a connector-lug normally engaged in said receiving socket of said sleeve, a hand-knob projecting from the front wall of said casing, said knob having a shank journaled in said rotary member, and lever means on the inner end of said shank for operating said movable means upon the turning of said knob to disengage said connector-lug from 10 said receiving socket of said sleeve prior to imparting rotative movement to said rotary member.

5. In a lock, the combination with a bolt mechanism of a rotary actuating cam therefor, said cam having a guideway and a central outwardly extended bearing opening, a knob having a shank journaled in said bearing opening, the inner end of said knob shank having oppositely extending lever 25 lugs normally vertically disposed within said guideway, slide-blocks movable in said guideway and arranged respectively on either side of said lever lugs, spring means for normally pressing said slide-blocks toward said lever lugs, one of said slide-blocks having a connector lug projecting outwardly 30 from its face, a key actuated mechanism, a rotary sleeve journaled in the rear wall of said casing, a coupling tongue interconnecting said key actuated mechanism with said sleeve, and said sleeve having in its body a receiving socket in which said connector-lug is normally engaged.

6. In a lock, a casing, a bolt device for projection from said casing, a bolt operating means, a pivoted detent tumbler for holding said bolt against operative movement, a rotary member having peripheral cam means for releasing said detent means, said rotary member being journaled in the outer wall of said casing, said rotary member having an actuator-lug for actuating said bolt operating means, said rotary member being further provided with a guideway and a central outwardly extended bearing opening, a knob having a shank journaled in said bearing opening the inner end of said knob shank having oppositely extending lever lugs normally vertically disposed within said guideway, slide-blocks movable in said guideway and arranged respectively on either side of said lever lugs, spring means for normally pressing said slide-blocks toward said lever lugs, one of said slide-blocks having a connector-lug projecting outwardly from its face, a key actuated mechanism, and means operated by said key actuated mechanism normally engaged by said connector-lug to couple said key actuated mechanism with said actuating cam.

6. In a lock, a casing, a bolt device for projection from said casing, a bolt operating means, a pivoted detent tumbler for holding said bolt against operative movement, a rotary member having peripheral cam means for releasing said detent means, said rotary member being journaled in the outer wall of said casing, said rotary member having an actuator-lug for actuating said bolt operating means, said rotary member being further provided with a guideway and a central outwardly extended bearing opening, a knob having a shank journaled in said bearing opening, the inner end of said knob shank having oppositely extending lever lugs, slide-blocks movable in said guideway and arranged respectively on either side of said lever lugs, spring means for normally pressing said slide-blocks toward said lever lugs, one of said slide-blocks having a connector-lug projecting outwardly from its face, a key actuated mechanism, and means operated by said key actuated mechanism normally engaged by said connector-lug to couple said key actuated mechanism with said rotary member.

7. In a lock, a casing, a bolt device for projection from said casing, a bolt operating

means, a pivoted detent tumbler for holding said bolt against operative movement, a rotary member having peripheral cam means for releasing said detent means, said rotary member being journaled in the outer wall of said casing, said rotary member having an actuator-lug for actuating said bolt operating means, said rotary member being further provided with a guideway and a central outwardly extended bearing opening, a knob having a shank journaled in said bearing opening, the inner end of said knob shank having oppositely extending lever lugs normally vertically disposed within said guideway, slide-blocks movable in said guideway and arranged respectively on either side of said lever lugs, spring means for normally pressing said slide-blocks toward said lever lugs, one of said slide-blocks having a connector lug projecting outwardly from its face, a key actuated mechanism, a rotary sleeve journaled in the rear wall of said casing, a coupling tongue interconnecting said key actuated mechanism with said sleeve, and said sleeve having in its body a receiving socket in which said connector-lug is normally engaged.

8. In a lock mechanism, a semi-circular rotary bolt having an inwardly extending radial arm at one end for pivotally mounting the same, a tail-piece pivotally connected with said radial arm, said tail-piece having an opening in its rear end and a longitudinal guide slot extending forwardly from said opening, a fixed guide-post embraced by said guide slot, a rotary actuating means cooperating with said tail-piece opening, said actuating means having a movable connector-lug, a key actuated means with which said connector-lug is normally engaged, and a hand-knob associated with said actuating means whereby a turning movement imparted to said knob will move said connector-lug to disengage the same from said key actuated means prior to imparting operative rotative movement to said rotary actuating means.

9. In a lock mechanism, a semi-circular rotary bolt having an inwardly extending radial arm at one end for pivotally mounting the same, a tail-piece pivotally connected with said radial arm, said tail-piece having an opening in its rear end and a longitudinal guide slot extending forwardly from said opening, a fixed guide-post embraced by said guide slot, a rotary actuating means cooperating with said tail-piece opening, said actuating means having a guideway and a central outwardly extended bearing opening, a knob having a shank journaled in said bearing opening, the inner end of said knob shank having oppositely extending lever lugs, slide-blocks movable in said guideway and arranged respectively on either side of said lever lugs, spring means for normally

pressing said slide-blocks toward said lever lugs, one of said slide-blocks having a connector-lug, and a key actuated means normally engaged by said connector-lug.

- 5 10. In a lock mechanism, a semi-circular rotary bolt having an inwardly extending radial arm at one end for pivotally mounting the same, a tail-piece pivotally connected with said radial arm, said tail-piece having an opening in its rear end and a longitudinal guide slot extending forwardly from said opening, a fixed guide-post embraced by said guide-slot, a rotary actuating means cooperating with said tail-piece opening, 15 said actuating means having a guideway and a central outwardly extended bearing opening, a knob having a shank journaled in said bearing opening, the inner end of said knob shank having oppositely extending lever lugs, slide blocks movable in said guideway and arranged respectively on either side of said lever lugs, spring means for normally pressing said slide-blocks toward said lever lugs, one of said slide-blocks having a connector-lug, and a key actuated mechanism, 20 a rotary sleeve, a coupling tongue interconnecting said key actuated mechanism with said sleeve, and said sleeve having in its body a receiving socket in which said connector-lug is normally engaged.
- 25 11. A lock mechanism, comprising a casing having at one end a pair of openings, a semi-annular rotary bolt having an inwardly extending radial arm at one end, a pivot stud upon which the free end of said radial arm is journaled, said rotary bolt being positioned to move through said casing openings when rotated, a tail-piece within said casing pivotally connected with said radial arm, said tail-piece having an opening in its rear end and a longitudinal guide slot extending forwardly from said opening, a fixed guide-post embraced by said guide slot, said bolt having detent notches at its 30 respective ends, a pivoted detent tumbler normally engaging a detent notch, a rotary actuating means journaled in the outer wall of said casing, said actuating means having peripheral cam means for releasing said detent means, said actuating means having an actuator-lug for cooperating with the opening of said tail-piece, a movable connector-

lug associated with said actuating means, a key actuated means with which said connector-lug is normally engaged, and a hand 55 knob for operating said actuating means and its connector-lug.

12. A lock mechanism, comprising a casing having at one end a pair of openings, a semi-annular rotary bolt having an inwardly 60 extending radial arm at one end, a pivot stud upon which the free end of said radial arm is journaled, said rotary bolt being positioned to move through said casing openings when rotated, a tail-piece within said casing pivotally connected with said radial arm, said tail-piece having an opening in its rear end and a longitudinal guide slot extending forwardly from said opening, a fixed guide-post embraced by said guide slot, 65 said bolt having detent notches at its respective end, a pivoted detent tumbler normally engaging a detent notch, a rotary actuating means journaled in the outer wall of said casing, said actuating means having peripheral cam means for releasing said detent means, said actuating means having an actuator-lug for cooperation with the opening of said tail-piece, said actuating means having a guideway and a central outwardly extended bearing opening, a knob having a shank journaled in said bearing opening, 70 the inner end of said knob shank having oppositely extending lever lugs, slide-blocks movable in said guideway and arranged respectively on either side of said lever lugs, spring means for normally pressing said slide-blocks toward said lever lugs, one of said slide-blocks having a connector-lug, a key actuated mechanism, 75 a rotary sleeve, a coupling tongue interconnecting said key actuated mechanism with said sleeve, and said sleeve having in its body a receiving socket in which said connector lug is normally engaged.

In testimony, that I claim the invention set forth above I have hereunto set my hand this 30th day of December, 1921.

JOSEPH SCHECHTER.
